CONTROL INSTRUMENT PANEL

William F. Stahl, Warminster, Pa., assignor to
Honeywell Inc., a corporation of Delaware

Filed Jan. 15, 1965, Ser. No. 83,461

Term of patent 14 years

(Cl. D52—6)

715.1

FIG. 2

FIG. 3

FIGURE 1 is a perspective view of a control instrument panel, showing my new design;

FIGURE 2 is a front elevational view of one of the control instruments making up the panel shown in FIGURE 1;

FIG. 3 is a side elevational view of FIG. 2.

The broken line instruments in FIGURE 1 are intended to be a repetition of the full line instruments therein shown. The panel is shown broken away in FIGURE 1, and in FIGURE 3 a fragmentary broken line portion of the housing of the instrument is shown, all broken line portions being for convenience of illustration and for illustrative purposes only.

I claim:

The ornamental design for a control instrument panel, substantially as shown and described.
